Samuel O. Merriman of Burlington, Connecticut,
Letters Patent.

The Schedule referred to in this Letter Patent and making part
of the same, containing a description in the words of the said
Samuel O. Merriman himself of his improvement in cutting the
teeth of circular and other gears, and also for cutting the same used
for cutting gears, and in the machinery necessary for effecting
the same, and that the following is a full and exact description
thereof. My invention and improvement consists in . . . combi-
ning the motion of a circular index or graduate with the teeth
of the punch, in cutting the teeth.

To all to whom these presents shall come: Be it known that
I Samuel Green Merriman of Burlington in the County of
Hartford and State of Connecticut have invented a new and
useful improvement in the mode and method of cutting the teeth
of circular and other gears, and also for cutting the same used
for cutting gears, and in the machinery necessary for effecting
the same, and that the following is a full and exact description
thereof. My invention and improvement consists in . . . combi-
ning the motion of a circular index or graduate with the teeth
of the punch, in cutting the teeth.

This may be effected by the following machinery connected with
my press, properly constructed for punching or stamping iron
or other metals. To such a press, considering it as standing in its
usual position. I attach two projections or studs to the front
part of the frame, both below the die in the press, at a distance
of twelve inches apart, one directly above the other, and projecting
from six to twelve inches more or less according to the size of the gear
to be cut. To a hole or box be made in each of these projections, one
inch or more in diameter. Into these boxes let the axis (marked
A in the annexed drawings) be inserted perpendicular about twelve
inches in length, having two bearings or shoulders so fitted as to re-
volve steadily in said boxes and having the upper end as high or
higher than the die in the press. To the lower end of this axis
fix horizontally the index or graduate marked B which is a circu-
lar metallic plate having a hole in the centre of the proper size
to fit on to the lower end of said axis, when it is firmly secured

by, or not. This plate or index should have the same number of no. 11, or indentations on the circumference as intended to cut teeth in the saw. At the upper end of said bar attach horizontally and fasten with a nut the plate intended to be cut into a saw, having a hole punched in the center for that purpose and let the bar be so placed that when it revolves it will bring the edge of the plate on to and directly over the die in the press. In the back part of the frame of the press, is inserted a pivot and on this pivot is placed an upright lever (marked C) in or near the center of the pivot marked D, so as to move freely on the pivot. The upper end of the lever being bent inward and over a projection on the moveable part of the press. On the lower end of the lever at the point (marked E) by a joint, attach a horizontal rod (marked F) of the press length and direction, having the end a little sharpened or tapered so as to play into the indentations of the circular index being supported at the end near the index by a plate or loop fastened to the press, or its frame so as to keep it in the same plane with the index. The die and punch in the press must of course be suitable for cutting the teeth required. At the lower end of the lever near the joint, a spring, or weight is, attached to draw back the horizontal rod as hereafter mentioned. When the press with this machinery attached is put in motion for use, the aforesaid moveable part as it rises will project, projecting against the upper or lower end of the lever, the effect of which will be to pull the sharpened end of the horizontal rod into the notch in the index, and cause it with the bar and the plate to revolve, and as the upright moveable part of the press falls, the weight or spring will draw back the horizontal rod into the next indentation of the index. This rod is constantly pressed over the index by a spring marked in the drawings C. Thus every time the press rises, the index and plate by means of the lever will revolve so as to keep the teeth required. and each fall of the press will by means of the punch and die cut out a piece from the

The plate so as to form a tooth, and at the same time the spring's weight will draw back the horizontal rod to the usual position.

The index may be formed by placing pins at a proper distance near the circumference of the index, and at right angles with it, and in many other . . . . ways, in which case the pins should be made to correspond with the index and the operation will be the same. If it is required to cut a saw with a straight edge the same index may be used, and the plate to be set placed upon the dies of the press, and to move in a right line by means of a rack and pinion attached to the arbor. When it shall be required to cut a saw plate with half the number of teeth as the index this may be effected by causing the rising frame of the press, with its projection to rise so high as to force the horizontal rod to push the index into notches, instead of one at each rise and . . . fall. Different dies and punches may be used if necessary. For a more full illustration reference may be had to the drawings annexed as part of this specification, and to the model deposited in the patent office.

From the operation of this machinery saw teeth are cut with great expedition and great accuracy, and as a result from this invention it is no longer necessary that a saw plate should be made exactly circular before the teeth are cut. Nor if a square or any irregular plate is brought under the operation of this improved machine it will not perfectly produce a saw perfectly circular, of course much trouble and expense is saved in preparing the plates. I do not claim as my invention the press or other machinery heretofore used, for cutting the teeth of saws by punch and die; nor do I claim as my invention an index graduated as such, singly, and alone, both have been long known and used separately. But I do claim as my invention the combination or combined use of the index graduated with the punch and die connected with any machinery or press for cutting saw teeth at all or any

descriptions in the manner and on the principles, as, specified
above, and for that combination and the machinery nec-
essary to effect the same, as above specified, of solid letters
Patent. Dated this 19th day of March 1836.

Ex't. Witness,
H. C. Romeo Sawyer
Rogersville (Missouri)
